UNITED STATES PATENT OFFICE.

JOSEPH BOUTEILLE, OF PARIS, FRANCE.

INTERNAL-COMBUSTION ENGINE.

1,167,376.

Specification of Letters Patent. Patented Jan. 11, 1916.

Application filed July 13, 1914. Serial No. 850,607.

To all whom it may concern:

Be it known that I, JOSEPH BOUTEILLE, a citizen of the French Republic, residing at 40 Rue Poussin, Paris, in the Republic of France, have invented certain new and useful Improvements in Internal-Combustion Engines, of which the following is a specification.

This invention relates more particularly to engines having a progressive internal combustion by injecting liquid fuel in order to afford said engines a better thermic efficiency, avoid deposits of hardly volatile matter, and still facilitate the control and construction.

The invention consists in decreasing mechanically the compression chamber either wholly or in part during the working stroke and injecting at the same time the liquid fuel.

The accompanying diagrammatic drawings show in Figures 1 and 2 two constructions embodying the present invention.

In carrying the invention into effect as illustrated in the diagrammatic section shown in Fig. 1, a cylinder 1 is provided in which a driving piston 2 reciprocates and acts similarly to other engines, upon the shaft 3 through the medium of the rod 4 and the crank 5. The compression chamber is reduced in a cylinder 6 having a volume determined by tests, with respect to the volume of the whole 1 and 2. In this cylinder 6 there is arranged a piston 7 connected to the piston 2 by a rod 8. A suction valve 9 which may be automatic or controlled, will permit of the admission of air at the desired time as shown by the arrow 10 and an exhaust valve 11 will also permit of the egress of the burnt gases at the desired time.

The injection of the fuel is effected by means of a suitable pump in proximity to the passage existing between the cylinders 1 and 6, that is to say, where the compressed air of the cylinder 6 escapes during the working stroke of the pistons 2 and 7. This liquid fuel will be ignited at the time it is injected by known means for instance, by a spark produced at the sparking plug 12.

The operation of the engine is as follows: Assuming the pistons 2 and 7 connected by a rod 8, to be at the top of their stroke and that the shaft 3 rotates in the direction indicated by the arrow 13, these pistons will, when descending, produce a suction of air through the valve 9 as the piston 2 is larger

than the piston 7 and also as both have the same linear velocity. Once the cylinder 1 is filled with air, the valve 9 closes and the piston 2 rising will compress in the space 60 left by the piston 7 in the cylinder 6, this quantity of air right up to the top of the stroke. Liquid fuel is then injected (into the zone between the cylinders 1 and 6) as indicated by the arrow 14, and this liquid 65 is ignited in the carbureting air. The pistons descend and the fuel will form with this compressed air a real blow-pipe, the flame 15 of which raises the temperature of the gases and thus constitutes the motive 70 pressure. The exhaust of the combustion gases is effected on the return of the piston to the upper part and so on.

Fig. 2 shows a modification of the manner in which the invention may be carried into 75 effect. The cylinder 6 and the piston 7 are located laterally of the cylinder 1 and the piston 2 at a greater or lesser distance, the injection and ignition being effected again in the part connecting the two chambers. 80 This disposition permits of displacing angularly the movement of the piston 2 with respect to that of the piston 7, of varying the stroke of the piston 7 according to the length of the crank 16 and of rotating the shaft 17 85 at a speed different to that of the shaft 3. These two speeds are obtained by connecting together the shafts 3 and 17 through the medium of a gearing or by a chain 18; they may be also combined into one. The operation is similar to that of the construction 90 shown in Fig. 1.

The advantages obtained by the application of the invention are numerous. The facility is afforded of giving the volumes 95 1-2 and 6-7 (compression) the desired proportions and of having a high thermic efficiency; of being able to operate with a small charge but with a complete compression; there is also a progressive mixing of 100 the air with the fuel thus producing a more homogeneous combustion and avoiding deposits of hardly volatile matter.

It is obvious that the described dispositions have only been given by way of example.

The invention is not only applicable to four-stroke-cycle engines but also to two-stroke-cycle engines, to engines having one or more cylinders with or without valves. 110 The ignition may be of any kind, electric with a direct spark, by means of burners or

spontaneous. The variations in power may be obtained by the variation of the quantity of the liquid injected, by the quantity of air admitted or by both means together.

5. What I claim and desire to secure by Letters Patent of the United States is:—

1. In an internal combustion engine operated by progressive internal combustion, in combination, a working cylinder with air-inlet and exhaust valves, a relatively small compression cylinder thereon, a piston for said working cylinder, a piston for said compression cylinder, a positive connection for said pistons, an ignition device carried by said working cylinder, and a fuel admission inlet arranged at the mouth of said compression cylinder substantially as and for the purpose described.
10. 2. In an internal combustion engine oper-

ated by progressive internal combustion, in combination, a working cylinder with air inlet and exhaust valves, a relatively small compression cylinder thereon, a piston for said working cylinder, a piston for said compression cylinder, a positive connection for said pistons, an ignition device carried by said working cylinder, and fuel admission means at the mouth of said compression cylinder adapted to admit fuel progressively during the working stroke of the engine, substantially as described.

In testimony whereof I affix my signature in presence of two witnesses.

JOSEPH BOUTEILLE.
